Attorney

UNITED STATES PATENT OFFICE.

JOHN P. REINECKE, OF LORAIN, OHIO, ASSIGNOR TO THE HOFFMAN HEATER COMPANY, OF LORAIN, OHIO, A CORPORATION OF OHIO.

GAS-VALVE STRUCTURE.

Application filed April 20, 1923. Serial No. 633,507.

To all whom it may concern:

Be it known that I, JOHN P. REINECKE, a citizen of the United States, residing at Lorain, in the county of Lorain and State of Ohio, have invented a certain new and useful Improvement in Gas-Valve Structures, of which the following is a full, clear, and exact description.

This invention relates to a gas regulating valve for use in connection with gas burners.

The object of the invention is to provide a gas burner in which the flow of gas is controlled by an inside adjustable member which is easily accessible for regulating purposes.

Reference should be had to the accompanying drawing forming a part of this specification in which the figure is a sectional elevation.

Referring to the drawing, 1 indicates a body portion which has an extension 2 which is threaded, as indicated at 3, this portion being adapted for connection to the feed gas pipe of a stove, or the feed gas pipe of any construction in connection with which the herein described device may be used.

There is also an extension at right angles to the extension 2 which is indicated at 4. This extension is hollow, and at its outer end is provided with an exit opening 5. The end of the extension 4 terminates in a conical slanting portion 6, which may be generally speaking conical in shape, and the opening 5 is at the upper or end portion of the slanting part 6. Upon the outer surface of the extension 4 there are threads 7, and upon these threads there is a nut 8. This nut may be adjusted to any desired position upon the thread 7, thereby determining the distance which the extension 4 will extend inside of the mixer of the usual burner.

There is an axial passageway 9 which extends through the extension 2 and it communicates with an enlarged chamber 10 which is formed in the member 1. The member 1 and the extension 4 are hollow, and threaded into an opening 1^a at the lower portion of the body 1 is a threaded barrel portion 11. Extending from this barrel portion is a hollow tubular part 12 which is provided with openings 13, at a portion thereof so that they communicate with the chamber 10, and gas which passes through the passageway 9 and to the chamber 10 will,

through the openings 13, pass inside of the 55 tubular member 12.

This tubular member is at its outer end provided with a conical end portion 14 which conical portion is provided with an opening 15 at the top thereof, and with a plurality 60 of openings 16 formed in the conical wall portions.

The member 11 and the tubular member 12 are capable of adjustment within the member 1, this adjustment being effected by 65 means of a knurled head portion 17 which is formed as a part of or connected to the barrel portion 11. A lock nut 18 is threaded upon the threads of the outer surface of the barrel portion 11, and is adapted to engage 70 with the lower end of the body portion 1 so as to hold the barrel part 11 and the hollow tubular portion 12 in any adjusted position.

When the tubular member 12 is extended to its most outward position the conical portion will extend up into the opening 5 and the conical walls of the member 12 will engage with the edge of the opening 5 so that gas passing through the tubular member 12 can find exit only through the opening 15. 75

If it be desired to supply more gas through the orifice 5 then the tubular member 12 is moved inwardly in the manner before described, so that the conical wall portion 14 is out of engagement with the lower or inner edge of the opening 5, and under these conditions gas may pass through the openings 16 and around the outside of the conical portion 14, and through the orifice 5. The extent to which gas may thus flow will, 80 of course, depend upon the clearance between the conical portion 14 and the inner edge of the orifice 5.

It will be noted that the adjustable tubular member 12 will at its outer end be guided 85 by the inner walls of the extension 4 so that the co-operation between the conical portion 14 and the outlet 5 will be assured.

By the structure which has just been described the member necessary to be moved in effecting an adjustment for the quantity of gas to be delivered, is readily accessible being entirely beyond the pipe which feeds gas through the valve structure.

The arrangement of parts which has been described also has the advantage of increasing the flow of gas to its maximum capacity because of the fact that the orifice in the 105

central adjustable tubular member is in line with the orifice in the outside fixed extension carried by the body portion of the device.

5 When the inside adjustable tubular member is adjusted for maximum flow of gas, the jet effect of gas passing through the central opening in the tubular member assists to draw the gas along with it. Additionally, this straight jet has a decidedly improved effect upon the siphoning action for entraining air as it passes into the mixer of a burner.

Having described my invention, I claim:—

- 15 1. A gas valve comprising a tubular body having at one end a tapering wall provided with an axial discharge opening and a gas inlet adjacent the opposite end, a tubular member within said body and adjustable longitudinally thereof, said tubular member being of less diameter externally than the internal diameter of the body whereby an annular passageway from the inlet to the discharge opening is provided upon the exterior of the tubular member, said tubular member having openings in the wall thereof establishing communication with said passageway and a tapering end portion adapted to be moved into engagement with the discharge end of the body to close said annular passageway, said end portion of the tubular member having an axial opening of less diameter than the discharge opening of the body.
- 25 2. A gas valve comprising a tubular body having an end wall provided with a conical inner surface and an axial discharge opening, said body having a lateral gas inlet, a tubular member within said body and adjustable longitudinally thereof, said tubular member being of less diameter than the tubular body whereby an annular passageway is formed between said tubular member and tubular body, said tubular member having a closed lower end which fits within the lower end of the body and forms a clo-

sure therefor, said tubular member having openings communicating with the passageway and a conical end portion adapted to engage in the discharge opening of the body and close the annular passageway, said end portion of the tubular member having an opening in axial alignment with the discharge opening of the body.

3. A valve comprising a body portion having an extension with a gas passage therethrough and capable of being connected with a gas feed pipe, said body portion having an opening at right angles to the extension just mentioned, and having a hollow extension which is in alignment with the opening in the body portion just mentioned, said extension at its upper end having a slanting wall portion and an outlet orifice which is centrally disposed with respect to said extension, a movable tubular member within said hollow extension said tubular member being guided in its movement by the inner walls of said extension of the body portion said tubular member at its outer end having slanting walls, with an orifice which is in axial alignment with the outlet orifice before mentioned, the said slanting walls having openings which are not in alignment, said tubular member at the end thereof being provided with openings which communicate with the gas passageway in the first mentioned extension for the body portion, a barrel portion connected with the tubular member said barrel portion having a threaded exterior and engaging with threads upon the interior of an opening in the body portion, a knurled head connected with said body portion whereby the tubular member may be moved toward and from the outlet opening with which it co-operates to control the passage of gas therethrough.

In testimony whereof, I hereunto affix my signature.

JOHN P. REINECKE.
